CLAIM

The ornamental design for a utility vehicle front seat, as shown and described.

DESCRIPTION

FIG. 1 is a perspective view taken from a front, left side of a utility vehicle front seat according to my design;

FIG. 2 is a perspective view taken from a rear, left side thereof;

FIG. 3 is a perspective view taken from a front, right side thereof;

FIG. 4 is a perspective view taken from a rear, right side thereof;

FIG. 5 is a front elevation view thereof;

FIG. 6 is a right side elevation view thereof;

FIG. 7 is a left side elevation view thereof;

FIG. 8 is a rear elevation view thereof; and,

FIG. 9 is a top plan view thereof.

Throughout the Figures, where shown the broken lines are included for the purpose of illustrating environment of the design and form no part of the claimed design.
